(57) CLAIM

I claim the ornamental design for a knife, as shown and described.

DESCRIPTION

FIG. 1 is a front perspective view illustrating my new knife design with the knife in a fully open position;

FIG. 2 is a front, perspective view thereof with the knife in a fully closed position;

FIG. 3 is a rear perspective view thereof with the knife in a fully open position;

FIG. 4 is another rear perspective view thereof with the knife in a partially open position;

FIG. 5 is a fragmentary, front perspective view thereof with the knife in a partially open position; and,

FIG. 6 is a fragmentary, front perspective view of the handle of the knife with the knife in a fully closed position.
